FOREIGN PATENT DOCUMENTS

EM 008927826-0001 * 4/2022

Primary Examiner — T Chase Nelson
Assistant Examiner — Kelly L Gross(57) **CLAIM**

The ornamental design for disinfection equipment as shown and described.

DESCRIPTION

1. Disinfection equipment

1.1 : Front

1.2 : Back

1.3 : Top

1.4 : Bottom

1.5 : Left

1.6 : Right

1.7 : Perspective

The portions of the disinfection equipment shown in broken lines form no part of the claimed design.

1 Claim, 7 Drawing Sheets
